UNITED STATES PATENT OFFICE.

WILLIAM O. KENNINGTON, OF BLOOMFIELD, NEW JERSEY, ASSIGNOR TO THE SIMMS MAGNETO CO., INC., OF NEW YORK, N. Y., A CORPORATION OF NEW YORK.

ELECTRICAL CONNECTOR.

1,039,542.

Specification of Letters Patent. Patented Sept. 24, 1912.

Application filed October 10, 1911. Serial No. 653,971.

To all whom it may concern:

Be it known that I, WILLIAM O. KENNINGTON, a subject of the King of Great Britain, residing at Bloomfield, in the county 5 of Essex and State of New Jersey, have invented certain new and useful Improvements in Electrical Connectors; and I do hereby declare the following to be a full, clear, and exact description of the invention, such as will enable others skilled in the 10 art to which it appertains to make and use the same.

My invention consists in the novel features hereinafter set forth, reference being 15 had to the accompanying drawing, which illustrates an embodiment of the invention which I have selected for purposes of illustration and said invention is fully disclosed in the following description and claims.

20 The object of my invention is to provide a connector for securing a flexible electric conductor, such as an electric cable composed of a plurality of small wires, or other form of electric conductor, to a stationary 25 part in such manner as to secure good contact and at the same time prevent the conductor from becoming accidentally disengaged and also to prevent injury to the conductor itself which might weaken or break 30 the same.

In the accompanying drawing I have selected for purposes of illustration an embodiment of my invention which is particularly desirable for the purpose of connecting 35 a conducting cable composed of fine wires with a part of a magneto electric machine, the particular embodiment herein shown being advantageously employed (for example) for connecting the low tension terminal of 40 a magneto electric machine to the commutator thereof, but it is obvious that the construction could be employed for other purposes and in other relations without departing from the invention.

45 In the said drawing, Figure 1 is an elevation of the connector having one end of the cable inserted and secured therein. Fig. 2 is a sectional view of the same. Fig. 3 is a sectional view showing the parts of the 50 connector detached and the end of the cable in elevation.

In the embodiment of the invention herein shown, 1 represents a metallic sleeve which I term the "cable end," said sleeve having

on its exterior preferably a knurled portion 55 1^a for convenience in holding the sleeve and being provided with a longitudinal bore 2 of a diameter to accommodate the cable with its insulating covering indicated at 16. At one end of the sleeve the central bore is enlarged as indicated at 4 and internally screw threaded and a conical seat 3 is formed at the point where the bore 2 of smaller diameter joins the bore 4 of larger diameter.

5 represents what I term for convenience, 65 the nipple which consists of a metallic sleeve provided at one end with a flared portion 6, the exterior conical surface of which is adapted to fit upon the conical seat 3 of the sleeve 1, while the inner surface of the flared 70 portion 6 forms a conical seat 7. The central aperture or bore of the sleeve 5 is also reamed out at the opposite end of the sleeve as indicated at 8, in order that there shall be no sharp edge at that point to engage the 75 cable wires.

10 represents the terminal screw or screw plug, which is provided at one end with a conical portion 11, adapted to fit the seat 7 of the nipple and said plug is provided adjacent to the conical tip 11 with a threaded portion 12 to engage the threaded larger bore of the cable end or sleeve 1. The terminal screw or plug 10 is also provided with a threaded projection 13 adapted to be 85 screwed into and firmly engage the stationary part to which the cable is to be connected.

In using this device, a portion of the cable insulation 16 is cut away as indicated in Fig. 90 3 to expose a length of cable slightly longer than the nipple 5. The end of the cable is then passed through the sleeve 1 and the exposed portion of the cable wires are passed through the nipple 5 until the smaller end 95 of the nipple engages the insulation 16. The fine wires of the cable are then pressed outwardly into circular form in all directions, as indicated in Fig. 2 and the cable and nipple are then carefully drawn back 100 into the sleeve until the flange 6 of the nipple comes in contact with the seat 3 of the cable end or sleeve 1. The terminal screw or plug is then screwed home, causing the conical end portion 11 to engage the separated cable wires and clamp them firmly against the conical seat 7 of the nipple, at the same time forcing the nipple flange 6

firmly into contact with the seat 3 of the cable end or sleeve 1. It will thus be seen that the cable is firmly secured in the connector, so that it is impossible that it should become accidentally disengaged. The seating of the conical tip 11 of the terminal screw or plug gives an extensive contact and a very intimate contact between the plug and the cable wires and the said wires 10 are also in contact with the nipple so that ample contact surface is secured. It will also be noted that the nipple terminates at its smaller end well within, or back from, the end of the cable end or sleeve 1, so that 15 a portion of the insulation 16 is held within the sleeve 1, thus preventing the angular bending of the cable wires adjacent to the connector and insuring the durability of the cable notwithstanding jar and vibration. 20 It is obvious that variations could be made in the construction without departing from the spirit of my invention. For example, instead of providing the terminal screw or plug with the threaded stem 13, 25 the screw plug may be provided with other means for connecting it rigidly to the stationary part to which it is to be attached this being simply an ordinary mechanical connection. I may also in some instances 30 dispense with the sleeve 5 and reduce the bore of the sleeve 1 adjacent to the seat 3 to substantially the size of the cable but I prefer the construction illustrated in Figs. 1, 2 and 3 for the reason that the cable can 35 be drawn entirely through the sleeve 1, the nipple 5 applied and the ends of the wires carefully spread out against the seat 7 of the nipple before the device is drawn back into the sleeve 1, thus facilitating the insertion 40 of the cable. It should also be understood that by duplicating the threaded portion 12 and conical tip 11 and dispensing with the threaded portion 13 and providing an additional sleeve 1 and nipple 5, the device 45 could be readily used for connecting together two sections of cable, which matter is so obvious that an illustration of the same is deemed unnecessary. It should also be understood that this device as herein shown, 50 can be used in connection with an ordinary insulated wire, if desired, in which case the extreme end portion of the wire can be bent into a circle to engage the seat 7 of the nipple and be held against the same by the terminal screw or plug. 55

What I claim and desire to secure by Letters Patent is:—

1. An electrical connector comprising a sleeve having a longitudinal aperture therethrough of a size to accommodate the conductor and its insulating coating, and provided with an interior seat, a detachable nipple having an internal diameter of a size to accommodate the conductor, located within said sleeve and provided with an outwardly extending flange to engage said seat, and a terminal plug having a threaded engagement with said sleeve and having a clamping portion adjacent to the flange portion of said nipple, for clamping portions 70 of the conductor against said flange and the flange against said seat. 60

2. An electric connector comprising a sleeve, provided with a longitudinal aperture therethrough, to accommodate the conductor and its insulating covering, said aperture being enlarged at one end of the sleeve, and threaded, and forming a conical seat within the sleeve, a tubular nipple located within the sleeve, but separable therefrom, said nipple having at one end a flange to engage the seat of said sleeve, provided with a conical seat on its outer surface, and having its bore at its opposite end enlarged to prevent injury to the conductor, and a terminal plug having a conical tip adjacent to the seat of the nipple, a threaded portion for engaging the interiorly threaded portion of the sleeve, and means for securing the plug to a stationary part. 75 80

3. An electric connector comprising a sleeve, having a longitudinal aperture of a diameter sufficient to accommodate the conductor and its insulating covering, and having a threaded portion at one end, a removable nipple within said sleeve, adapted to fit over the conductor, and having an outwardly extending flange at one end, means for preventing the nipple from being drawn through the sleeve in one direction, and a screw plug having a clamping part adjacent to the flanged portion of the nipple, and a threaded portion for engaging the threaded portion of the sleeve. 90 95 100

In testimony whereof I affix my signature, 105 in the presence of two witnesses.

WILLIAM O. KENNINGTON.
